CARPET SWEEPER WITH BRUSH PRESSURE CONTROL MEANS

Berthold R. Thiele, Ripon, Wis., assignor to Speed Queen Corporation, a corporation of Delaware

Application November 17, 1944, Serial No. 563,845

10 Claims. (Cl. 15—41)

1
The present invention relates to hand operated carpet sweepers of the type having a rotary sweeper brush mounted in a translatable case and driven by support wheels of the sweeper.

One object of the invention is to provide a novel sweeper of the above character which in normal operation applies downward pressure to the rotary brush proportionate to the downward force exerted by the operator on the sweeper and which is automatically operable, in instances in which the downward force on the sweeper is excessive, to limit the downward pressure on the brush to the optimum pressure requisite to a smooth and eminently efficient sweeping action. A related object is to provide a carpet sweeper in which the brush is protected from overloading either by excessive resistance between the brush and the floor covering or by excessive downward pressure on the sweeper to the end that the useful life of the brush and the sweeper is prolonged and wear on the floor covering is minimized.

A more specific object is to provide a carpet sweeper of the type recited having a novel brush and support wheel assembly integrated into the sweeper case in a manner whereby the brush is moved downwardly relative to the support wheels in response to increasing downward force on the sweeper up to a predetermined value, the brush and wheel assembly being responsive to downward pressure on the case above the predetermined value to float upwardly in the case for virtually terminating the downward movement of the brush relative to the wheels and at the same time limiting the downward pressure on the brush to that required for optimum sweeping action.

Other objects and advantages will become apparent as the description proceeds.

In the accompanying drawings:

Figure 1 is a top plan view showing a carpet 40 sweeper embodying the present invention.

Fig. 2 is a horizontal sectional view taken along line 2—2 of Fig. 3.

Fig. 3 is a vertical sectional view taken along line 3—3 of Fig. 2 with certain parts broken away for clarity in illustration.

Fig. 4 is a fragmentary sectional view taken along line 4—4 of Fig. 3 and showing the relationship of a typical wheel support to the casing guide therefor.

Fig. 5 is a fragmentary side view of one end of the sweeper of Fig. 1.

Fig. 6 is a fragmentary sectional view of one end of the sweeper casing.

Referring to the drawings it will be seen that

2
a carpet sweeper embodying the present invention comprises in general a case C supported on floor wheels F which also serve to drive a rotary brush B. For propelling the sweeper back and forth across the surface to be swept, a handle H is provided. The lower end of the handle H is connected to a bail H', the arms of which straddle the casing and are pivotally connected thereto. The means for automatically controlling the relative height of the brush B and floor wheels F and for automatically causing the brush B to float when excessive pressure is applied to the handle H is designated generally at M and of course is provided at both ends of the casing C. Dust pans (not shown) are pivotally supported in the lower part of the case on the opposite sides of the brush B.

The case C comprises an arched cover plate 15 extending longitudinally of the sweeper and two outwardly bulging end shells 19 attached to opposite ends of the cover plate with adjoining marginal edges of the plate and the respective shells disposed in overlapping engagement with each other. Two vertical end plates 10 are disposed within the case C and suitably attached to contiguous casing parts to have general alignment with the junctures between the cover plate 15 and the respective end shells 19. The vertical plates 10 support the internal working parts of the sweeper and also serve to partition the space enclosed within the case C into an inner sweeper compartment 90 under the cover plate 15 and two outer wheel compartments embraced by the respective end shells 19 (see Figs. 2 and 6).

The floor wheels F are rotatably mounted on stub axles 35. These axles 35 are riveted, welded or otherwise suitably secured to floating axle supports 36. These axle supports 36 are of a plate-like construction. They are mounted for floating movement in a vertical plane to permit both swinging movement, and fore and aft movement, in a slotted guide structure designated generally at 37. Each slotted guide structure comprises a pair of vertical plates 38 and 39 supported on the walls of the casing and having upper and lower spacers 40 and 41 to maintain them in closely spaced parallel relation. The guide plates 38 and 39 may be constituted of metal, or suitable rubber composition or plastic. The spacers 40 and 41 may be individual spacers or may be formed as an integral part of one or both guide plates. As shown, the spacers 40 and 41 are individual elements and are held in place by the same rivets 42 which secure the guide plates 38 and 39 to their end wall 10 (see Fig.

4). The intermediate portion of each floating axle support 36 is fitted for free movement in between the guide plates 38 and 39. The inner end of each axle support is forked or bifurcated as indicated at 43. These forked inner ends of the axle supports embrace journal sleeves 65 combined with the ends of the brush B in a manner which shall be hereinafter fully described. A spring designated generally at 50 is provided. It has an intermediate portion 51 anchored as at 52 to the contiguous end wall of the casing. Spring arms 53 are integral with the intermediate portion of the spring 50 and extend inwardly and downwardly at approximately a 45° angle. The lower ends of the spring arms 53 are transversely bent as at 54 and in the assembly, are inserted in slots 55 provided in the axle supports 36. These spring arms 53 are tensioned when they are forced or sprung into the slots 55. The tension thus set up in the spring arms 53 acts at an angle of 45° downward and also exerts an inward thrust on the axle supports 36. The vertical component of this force will press the axle supports against the lower spacers 41 while the horizontal component moves the axle supports 36 inwardly. The inward movement of the axle supports is stopped when the floor wheels F engage the brush pulleys 56 also combined with the ends of the brush B in a manner to be herein-after more fully described.

When the sweeper is in use the pressure normally applied to the handle H, will in effect, cause the wheels to move upward relative to the case. This upward movement of the wheels serves to lift the outer ends of the axle supports 36 against the vertical component of force exerted by the spring 50. The tension of the spring arms 53 however will hold the inner end of the axle supports down against the inner ones of the lower spacers 41 which act as fulcrums about which the axle supports 36 swing in a vertical plane. As a consequence of this upward swinging movement of the axle supports, the forked ends 43 thereof move the brush B downwardly thereby acting to obtain good brush contact with the floor covering. However, in the event excessive resistance in sweeping is met by the brush, or excessive pressure is applied to the handle, the reaction on the brush will cause the axle supports to float upwardly leaving the inner fulcrums 41. Consequently, the brush B will also float so that the complete wheel and brush suspension is lifted from the lower spacers 41, thereby limiting the pressure of brush contact so as to avoid undue wear and tear on the carpet or rug.

With the angular speed of the brush and its diameter fixed, the determining factor in the efficiency of sweeping is the pressure of the brush on the carpet. Too little pressure will not clean the carpet, too much will cause excessive wear on brush and carpet and not increase efficiency.

For the conventional type sweeper it is left to the operator to find the proper pressure necessary to be exerted on the handle. With the present invention no such experience or skill is necessary. When the pressure between the brush and carpet exceeds the maximum allowed the brush will rise relative to the wheels, the axle supports 36 will be lifted from the fulcrums and both the axle supports 36 and the brush B will float. Effective sweeping can of course be had, but excessive pressure of the brush on the carpet is avoided. A reduction in pressure will restore the normal positive relation.

As shown to advantage in Fig. 2, the body 60

of the brush B is provided at each end with an axial hole 61 and also has a recess 62 spaced from and surrounding the hole 61. A shrink cup 63 is driven into each recess 62 and is provided with a square opening axially aligned with hole 61. A brush axle 64, one at each end of the brush B, has its inner portion extended through the opening of its shrink cup 63 and is driven into the axial hole 61 to be rigidly secured to the brush. It may be desirable to have the hole 61 of circular cross section and the inner portions of the brush axle of square cross section to obtain the desired rigidity and the capacity to transmit torque. The portion of each brush axle which projects outwardly from its associated shrink cup 63 carries a journal sleeve 65 with which the forked ends 43 of the axle supports 36 are engaged. There are openings provided in the end walls 10 to accommodate these journal sleeves 65. The margins of these openings are provided with turned flanges 66 which coat with the journal sleeves to provide horizontal displacement of the brush B.

It will be noted that there is rather close contact between the prongs of the forked ends 43 of the axle supports 36 and the journal sleeves 65. However, this close contact exists only vertically; in the horizontal direction the forked ends 43 are open on their inner sides while there is a substantial clearance between the journal sleeves 65 and the body of the axle supports 36 at the outer sides of the forked formations. Hence, there can be no interference with the effective driving engagement between the floor wheels F and brush pulley 56 and the brush B may be removed by pulling the floor wheel F outwardly against the tension of the wheel spring 50 until the forked ends 43 of the axle supports 36 are disengaged from the journal sleeves 65.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

Subject matter disclosed in the instant application as originally filed but not claimed herein forms the subject matter of three copending applications Serial Nos. 230,129; 230,130; and 230,131, all filed June 6, 1951.

What I claim is:

1. A carpet sweeper comprising a case, a pair of floor wheels at each end of the case, a rotary brush having pulleys at its ends driven by the floor wheels, axles for the floor wheels, floating supports for the axles, said supports being interconnected with the brush to support it for rotation and constrain it to move down as the wheels move up relative to the case and vice versa until downward pressure on said case exceeds a predetermined value, a guide structure for each support on said case and confining said support for free floating movement in a vertical plane, stop means in said structure to limit downward movement of said support and to provide for swinging movement of said support in a vertical plane under normal operating conditions and to permit said support to freely float when downward pressure exceeding said predetermined value is applied to the case, and spring means mounted on the case and connected to the axle supports and acting to urge them downwardly with

a predetermined force and also inwardly to yieldably maintain their interconnection with the floor brush and driving engagement between the floor wheels and the brush pulleys.

2. A carpet sweeper comprising a case, floor wheels for the case, a rotary brush, axles for the floor wheels, a plate-like support for each axle, each plate-like support also being interconnected with the brush, a guide for each support comprising a pair of vertical plates supported on the case and having spacers between them to maintain them in closely spaced, parallel relation, each plate-like axle support being fitted between the plates of its guide for free floating movement, for swinging movement in a vertical plane about a lower spacer as a fulcrum and for fore and aft movement, and spring means connected to the axle supports and acting to urge them downwardly with a predetermined spring force and also inwardly.

3. A carpet sweeper comprising a case, floor wheels for the case, a rotary brush, having journals at its ends, axles for the floor wheels, a plate-like support for each axle, each axle being supported adjacent the outer end of its support, the inner ends of the supports being forked and embracing the journals of the brush to support the brush for rotation and control its vertical position, a guide for each support comprising a pair of vertical plates supported on the case and having spacers between them to maintain them in closely spaced, parallel relation, each axle support being fitted between the plates of its guide for free floating movement to permit swinging movement in a vertical plane about a lower spacer as a fulcrum and fore and aft movement, and spring means mounted on the case and connected to the axle supports to urge them downwardly with a predetermined force and also inwardly yielding to maintain their forked ends in cooperative engagement with the journals of the brush.

4. A carpet sweeper comprising a case, floor wheels for the case, a rotary brush, axles for the floor wheels, a support for each axle, a guide for each support, each guide being mounted on the case and having a horizontal slot extending therethrough fore and aft of the case, each axle being mounted on its support adjacent the outer end thereof, the inner ends of the supports being interconnected with the brush to support it for rotation and control its vertical position, the intermediate portion of each support being extended through the slot of its guide and being fitted therein for free floating movement, and spring means mounted on the case and connected to the axle supports to urge them downwardly with a predetermined force and also inwardly to yieldably maintain their interconnection with the brush.

5. A carpet sweeper comprising a case, floor wheels for the case, a rotary brush, axles for the floor wheels, a support for each axle, a guide for each support, each guide being mounted on the case and having a horizontal slot extending therethrough fore and aft of the case, each axle being mounted on its support adjacent the outer end thereof, the inner ends of the supports being interconnected with the brush to support it for rotation and control its vertical position, the intermediate portion of each support being extended through the slot of its guide and being fitted therein for free floating movement, a spring for each set of floor wheels, each spring having its body portion anchored on the case

and having downwardly and inwardly inclined spring arms connected to and tensioned to exert a predetermined downward force on the supports and also to urge them inwardly yieldably to maintain their interconnection with the brush.

6. A carpet sweeper comprising a case, four floor wheels therefor, a rotary brush, axles for the floor wheels, supports for the axles mounted for free floating movement in a vertical plane, stop means cooperating with each support to limit its downward movement, and spring means normally maintaining said supports against said stop means, each support being disposed for swinging movement in a vertical plane when in contact with said stop means under normal operating conditions, and being permitted to float bodily upwardly from said stop means when excessive downward pressure to overcome said spring means is applied to the case, said supports being interconnected with the brush to support said brush for rotation and operable when in contact with said stop means to constrain said brush to move down as the wheels move up relative to the case and vice versa.

7. A carpet sweeper comprising a case, four floor wheels for the case, a rotary brush, brush axles secured to the ends of the brush and projecting therefrom, journal sleeves fitted on the projecting ends of the brush axles, axles for the floor wheels, supports for the wheel axles, slotted guides mounted on the case, said supports extending through said guides for free universal floating movement in a vertical plane, stop means including a fulcrum on each of said guides for limiting downward movement of the associated support, the inner ends of said supports being forked and embracing the journal sleeves to support the brush for rotation and when in contact with said fulcrum to constrain said brush to move downwardly as the wheels move upwardly relative to the case and vice versa, and spring means urging said supports downwardly and inwardly.

8. A carpet sweeper comprising a case, floor wheels for the case, a rotary brush, axles for the floor wheels, supports for the axles, fulcrums underlying said supports, said supports being floatably engaged with the fulcrums and interconnected with the brush to support it for rotation and constrain it to move down as the floor wheels move up relative to the case and vice versa until the downward pressure on the case exceeds a predetermined force, and spring means carried by the case and connected to the axle supports to urge them downwardly normally against the fulcrums with a force equal to said predetermined force and also inwardly, the floating mounting of the axle supports permitting said supports to move upwardly away from said fulcrums whereby to cause the brush to float therewith when pressure applied to the case exceeds said predetermined downward force exerted by the spring means on the axle supports.

9. A carpet sweeper comprising a case, floor wheels for the case, a rotary brush, brush axles secured to the ends of the brush and projecting therefrom, journal sleeves fitted on the projecting ends of the brush axles, the end walls of the case having openings through which the journal sleeves extend, the margins of the openings being flanged and cooperating with the journal sleeves to prevent horizontal displacement of the brush, axles for the floor wheels, full vertically floating supports for the wheel axles, the inner ends of the supports being forked and embracing the journal

sleeves to support the brush for rotation and constrain it to move down as the wheels move up relative to the case and vice versa until the downward force on the case exceeds a predetermined value, slotted guides mounted on the case and in which the supports float, and spring means urging the supports downwardly and inwardly.

10. A carpet sweeper comprising, in combination, a casing, a pair of floor wheels at each end of said casing, a rotary brush having pulleys at opposite ends interposed between and in self-centering driving engagement with said wheels, axles for the floor wheels, guide members fixed on said casing between said pulleys and axles and defining horizontally disposed guide slots with 15 stop means at the bottom thereof, carrier plates extending laterally through said slots, said plates normally slidably and pivotally resting on said stop means and being bodily movable upwardly therefrom into position for free universal vertical floating movement in said slots, the outer ends of said plates journaled on said axles and the inner ends of said plates being bifurcated to embrace said pulleys to support said brush for vertical movement, and spring means acting directly 20 25

on said plates to urge them downwardly and inwardly, whereby pivotal movement of said plates on said stop means will cause downward movement of said brush upon upward movement of said wheels and vice versa and a predetermined pressure reaction on said wheels and brush will cause said plates to lift from said stop means.

BERTHOLD R. THIELE.
